J. A. SHANNER, OF PLAINVIEW, ILLINOIS.

Letters Patent No. 84,007, dated November 10, 1868.

IMPROVED MECHANICAL MOVEMENT.

The Schedule referred to in these Letters Patent and making part of the same.

To all whom it may concern:

Be it known that I, J. A. SHANNER, of Plainview, in the county of Macoupin, and State of Illinois, have invented a new and useful Improvement in Mechanical Movements; and I do hereby declare that the following is a full, clear, and exact description thereof, which will enable others skilled in the art to make and use the same, reference being had to the accompanying drawings, forming part of this specification, in which—

Figure 1 represents an elevation with a part of the casing removed;

Figure 2 represents a vertical sectional elevation; and

Figure 3 represents a detached view showing the valve.

Similar letters of reference indicate corresponding parts.

The nature of my invention relates to improvements in devices for operating pumps.

It consists in providing a toothed rack upon the pump-rod, and a pair of gear-wheels for operating it, one of which is turned by a hand-crank, gearing into the other, and provided with a toothed segment, which gears into the rack-teeth during a part of its revolution, and actuates it in one direction, and the other with a corresponding segment arranged to gear into the rack for a similar portion of time, to actuate the stem in the other direction, the said segments being so set on their respective wheels as to act alternately.

In the drawings, A represents the case for containing the operating-mechanism, and B, the tube.

C represents the lower end of the rod, which is bifurcated, as shown in fig. 3.

D represents the valve, which is pivoted between the bifurcated parts, and composed of two leaves, as shown in fig. 2, and each leaf is composed of a metal and a leather plate, the metal being designated by *a*, and the leather by *b*. The plates *a* are riveted to the leather plates, for the purpose of stiffening the same.

Springs *d* are secured near the axis of the valve, and arranged so that the upper ends bear upon the leaves in a manner to cause them to close readily with the sides of the tube at the moment of commencing the upward movement.

E represents a toothed rack, secured to the upper end of the pump-rod, provided with two rows of teeth.

F represents a driving-wheel, provided with a crank-shaft, and arranged to gear into the wheel G, arranged in the same vertical plane.

The wheel F is provided on its opposite side with a toothed segment H, and the wheel G with a corresponding toothed segment on its front side. These segments are so arranged, with reference to each other and the rack, as to be brought into gear with it alternately, and as they rotate in opposite directions, the rod is thereby actuated reciprocally.

It may not be necessary to construct the rack in two parts, if the segments be made of larger diameter than the wheels.

The means of actuating the pump-rod presents the advantage of requiring but little space, as the requisite amount of movement for the same may be obtained with wheels of quite small diameter.

The application of rotary motion by the hand is also preferable to reciprocating motion.

Having thus described my invention,
I claim as new, and desire to secure by Letters Patent—

The combination, with the wheels F and G, of the segments H and I, and the rack E, arranged to operate substantially as and for the purpose described.

J. A. SHANNER.
